UNITED STATES PATENT OFFICE.

CLARENCE W. COLEMAN, OF WESTFIELD, NEW JERSEY, ASSIGNOR TO
THE HALL SIGNAL COMPANY, A CORPORATION OF MAINE.

SIGNAL APPARATUS.

No. 806,238.

Specification of Letters Patent.

Patented Dec. 5, 1905.

Application filed July 1, 1905. Serial No. 267,876.

To all whom it may concern:

Be it known that I, CLARENCE W. COLEMAN, a citizen of the United States, and a resident of Westfield, in the county of Union and State 5 of New Jersey, have invented certain new and useful Improvements in Signal Apparatus, of which the following is a specification.

This invention relates to improvements in signal apparatus especially adapted for use on 10 railways and capable of operation by means of an electric motor.

The invention seeks to provide such an apparatus in which greater simplicity and compactness of the parts shall be obtained and in 15 which there shall be greater reliability and efficiency and less liability of derangement and improper working of the various parts. These objects are secured to a large extent by the particular arrangement of parts whereby the 20 power is applied to the thrust-rod which actuates the signal. This arrangement makes it possible to dispense with levers, racks, and chains in moving the signal from one position to another. It makes it possible to apply the 25 power of the motor directly to the signal-rod and in the direction of the latter's movement, thus effecting a considerable economy in the energy required to move the signal. It also makes it possible to employ a magnet or other 30 device which shall be stationary and have the function of controlling the connection between the signal or its thrust-rod and the motor or motor-driven parts.

This invention also makes it possible to employ a magnet or other device having the last-named function and having also the additional 35 function of controlling the device employed to lock the signal in the position in which it has been moved and having also the function 40 of controlling the supply of energy to the motor.

Where the invention is applied to operate a plurality of signals on the same post, such as home and distant signals, the advantages 45 above stated are especially marked, one motor serving to operate the signals.

In the accompanying drawings the invention is illustrated in one of its various embodiments and as applied to home and distant signals on 50 the same post.

Figure 1 is a side elevation of the apparatus looking in the direction of the arrow 1 in Fig. 2. Fig. 2 is a front elevation of the apparatus. Fig. 3 is a side elevation looking in the

direction of the arrow 3 of Fig. 2. Fig. 4 is 55 a sectional plan view taken on the line 4 4 of Fig. 2. Fig. 5 is a sectional side elevation showing the device for connecting the thrust-rod with the motor and for locking the thrust-rod in the position to which it has been moved. 6c Fig. 6 is a fragmental side elevation showing the power-wheel of the motor in the act of lifting the thrust-rod, the view being taken from the side opposite that shown in Fig. 5. Fig. 7 is a sectional plan view on the line 7 7 65 of Fig. 5. Fig. 8 is a sectional plan view on the line 8 8 of Fig. 5. Fig. 9 is a diagram showing the signals and circuits for two blocks of a railway.

Referring now to the particular embodiment 70 of the invention as shown in the drawings, the frame of the machine consists of the base 1, back ribs 2 and 3, upper yoke 4, and stirrup 5.

6 is an electric motor which drives gear-wheel 7, carried on the shaft 8, on which is 75 mounted pinion 9, meshing with the driving gear-wheel 10. The shaft 8 is supported by the uprights 11 and 12, bolted to the stirrup 5 at their lower ends and bolted at their upper ends to the yoke 4. These uprights 11 80 and 12 are provided with bearings for the shaft 13, which carries the driving-gear 10.

14 and 15 are the home and distant signals, (see Fig. 9,) mounted on the same post and operated by the signal-rods or thrust-rods 16 85 and 17, respectively. The lower ends of these thrust-rods carry dash-pot cylinders 18 and 19, respectively, to which they are directly connected, the axes of the dash-pots being in lines parallel with the lines of vertical 90 movement of their respective thrust-rods.

20 and 21, respectively, are reciprocating pieces operated by the power-wheel 10 and designed to engage with their respective thrust-rods to move the same upward, and thereby 95 shift the signals from danger to safety position. These pieces 20 and 21 may be guided by any suitable means; but as shown in the drawings they are guided by their thrust-rods, which they surround.

22 is a dog pivoted in the piece 20 and yieldingly pressed toward the thrust-rod 16 by spring 23.

24 is a U-shaped bracket secured to the side of the thrust-rod 16 by screws 25 and 26. 105 Pivoted to the bracket 24 is a latch 27, carried on the pin 28 and having a tooth 29 at its upper end and a roller 30 at its lower end. The

piece 20 engages the thrust-rod 16 to move it upward by the interlocking of dog 22 with tooth 29 of latch 27. The bracket 24 carries also a pivoted dog 31, designed to engage a latch 32 or other locking device to lock the thrust-rod in its upper position or the position to which it has been moved by the piece 20. The latch 32 is carried on shaft 33, pivoted on the frame and provided with a counterweight 34 and a long lever 35. The lever 35 swings back and forth in the same vertical plane as the roller 30 of latch 27.

When the lever 35 is held inward against the roller 30 and the piece 20 is moved upward, dog 22 engages latch 27 and moves the thrust-rod 16 upward until dog 31 engages latch 32 to hold the thrust-rod in the position to which it has been moved. So long as the lever 35 is held inward against roller 30 latch 32 will maintain the thrust-rod in its upper position. At the same time lever 35 will lock the latch 27 in its engaging position, although the piece 20 may move down from its engagement with the latch 27. It will be seen, therefore, that the lever 35 controls the engagement of piece 20 with thrust-rod 16 when the latter is to be moved and also controls the device or means for locking the thrust-rod in the position to which it has been moved.

30 In the preferred arrangement of the mechanism the piece 20 is operated by a cam and for this purpose has a flange 36, against whose under side the cam moves. Thus the piece 20 constitutes a cam-piece.

35 37 is the cam, which co-operates with the piece 20. In its best form and as shown in the drawings the cam 37 is in the form of a roller carried on a spoke of the power-wheel 10. When the rod 16 is in its lower or normal position, piece 20 is resting on the pin 85, between which and the tooth 29 of latch 27 the piece 20 has ordinarily a play of about an eighth of an inch.

38 is a magnet co-operating with an armature on the lower end of lever 35, which normally hangs with its armature against or close to the pole of the magnet.

In the operation of the parts above described the magnet is energized to hold the lever 35 inward and the motor is started. Lever 35 bears against roller 30, so as to hold the tooth 29 of latch 27 in the path of dog 22 on the piece 20. The latch 32 is also held inward, so as to engage with dog 31. As the power-wheel 10 travels in the direction of the arrow shown in Fig. 6 cam 37 engages with the flange 36 on the piece 20 and carries the piece 20 upward, as shown in Fig. 6. As the piece 20 moves upward its dog 22 engages 40 with the latch 27, and since the latch is locked against movement by the lever 35 thrust-rod 16 is carried upward along with the piece 20. During this movement the cam 37 moves from one end of the flange 36 to the other and back, 45 as shown in Fig. 6, and then out from under

the piece 20, whereupon the motor stops, permitting the piece 20 to drop down upon the stop-pin 85, fixed on rod 16. The spring 39 of the dog 31 permits the dog to snap past locking device 32, so that when the cam passes beyond the piece 20 the thrust-rod is supported on the locking device 32. When lever 35 is released, as by de-energizing magnet 38, the weight on the thrust-rod presses latch 32 back out of the way, so that the thrust-rod returns to its lower position. If for any reason the magnet 38 should be de-energized and the motor stopped after the thrust-rod has been more or less elevated and before cam 37 had moved out of engagement with the piece 20, the thrust-rod would, nevertheless, return to its lower position. In such case if dog 31 has passed latch 32 the latch would be pressed out of the way by the weight of the thrust-rod, and the weight of the thrust-rod bearing on the tooth 29 of latch 27 would cause the lower end of the latch to swing to the left, so as to disengage its tooth from dog 22. Thus the thrust-rod would be returned to its lower position, although the piece 20 would be still held in its upper position by the cam 37. It will therefore be seen that the thrust-rod has a movement independent of the piece 20. Thus it will be seen that by this arrangement the signal after having 50 been moved part way or all the way to safety position by the upward movement of the thrust-rod may return to "danger" at once as soon as magnet 38 is de-energized and without regard to the position of the motor or the power-wheel 10 or cam 37.

Magnet 38 has an aperture 40, which operates circuit-controllers 41, which control the circuit of the motor, as will hereinafter appear. When the magnet is energized, the circuit-controller 41 is closed and when it is de-energized the circuit-controller opens.

42 is a rod pivoted at its upper end to an L-shaped lever 43, which is pivoted at 44 on the yoke 4. The rod 42 is pivotally connected at its lower end with a crank-shaft 45, which operates circuit-breakers 46, 47, and 48.

49 is an arm carrying a roller 50 and secured to the bracket 24, carried on the thrust-rod 16.

When the thrust-rod 16 rises and has moved the signal to "safety," roller 50 comes against the upper end of lever 43, thereby elevating rod 42 and opening the circuit-breakers 46 and 47 and closing the circuit-breaker 48. When magnet 38 is de-energized to permit the thrust-rod 16 to move downward, roller 50 comes against the depending end of lever 43, turning it back on its pivot to its former position, thereby lowering rod 42 so as to close 120 the circuit-breakers 46 and 47 and open circuit-breaker 48.

The mechanism for the distant signal 15 operated by thrust-rod 17 is similar to that described with reference to the home signal 130

and thrust-rod 16 and need not be specifically described.

51 is the cam-roller cooperating with piece 21 on thrust-rod 17. It is fixed on the power-wheel 10 on the opposite side from cam 37 and one hundred and eighty degrees therefrom.

52 is the latch pivoted on the thrust-rod 17 and corresponding to latch 27 of thrust-rod 16.

53 is the lever corresponding to lever 35 and 10 carrying an armature at its lower end controlled by magnet 54 and controlling-latch 52.

55 is the locking device operated by lever 53 to lock the thrust-rod in its upper position and arranged to engage with dog 56 on thrust-rod 15 17.

57 is the circuit-breaker rod, corresponding to rod 42 and pivoted at its upper end to lever 58, corresponding to lever 43.

59 is the roller carried by thrust-rod 17 and 20 corresponding to roller 50 and operating to shift the lever 58 from one position to another.

Rod 57 operates circuit-breaker 60.

61 is the circuit-controller, operated by magnet 54.

After the motor has elevated thrust-rod 16 to put the home signal to "safety" it is free to continue its rotation to elevate thrust-rod 17 to put the distant signal to "safety." This latter operation will take place when magnet 54 is energized. When this happens, power-wheel 10 continues its rotation and cam 51 engages piece 21, which piece connects with thrust-rod 17 to put the distant signal to "safety," the distant signal being locked at "safety" by the latch 55, as heretofore described. When magnet 38 is deenergized, thrust-rod 16 is released and the home signal moves to "danger" by gravity. When both 40 magnets 38 and 54 are deenergized, both signals move to "danger."

In Fig. 9, 62 and 63 are two blocks of a railway provided with signals, such as heretofore shown and described, the signals being arranged to operate on the normal safety principle. The motor-magnets and other parts associated with the home and distant signals 14 and 15 in Fig. 9 have the same reference-numerals as are employed for the corresponding parts in the other figures. 64 is the track-magnet for block 62. 65 is the track-magnet for block 63. The circuit of the home-signal magnet 38 is from battery 66, circuit-controller 67, wire 68, wire 69, magnet 38, and wires 69 and 70 to battery. Since the signals are normally at "safety," this circuit, through magnet 38 and which is controlled by track-magnet 64, is normally closed. The circuit of the motor for operating the home signal 60 14 is from battery 66, wire 71, circuit-controller 41, wire 72, circuit-breaker 48, wire 73, motor 6, and wire 70 to battery. The circuit of the motor for the distant signal 15 is from battery 66, through wire 71, circuit-controllers 41 and 61, wire 74, circuit-breaker 60,

wire 75, motor 6, and wire 70 to battery. The normally closed circuit of the distant-signal magnet 54 is from battery 75 of the following station, wire 76, circuit-controller 77, wire 78, circuit-breaker 79, wire 80, circuit-breaker 46, wire 81, magnet 54, wires 82, 69, 70, and 83 back to battery. The operation 70

of the circuits is as follows: When a train enters block 62, it shunts magnet 64 and opens at 67 the circuit of home-signal magnet 38. 75 When magnet 38 is thus deenergized, it unlocks the home and distant signals 14 and 15, which had been previously locked at "safety" by their latches 32 and 55, so that the signals rise by gravity to "danger" behind the train. 80

As the signals move to danger position circuit-breakers 46 and 47 are opened and circuit-breakers 48 and 60 are closed. When the train passes out of block 62 and into block 63, magnet 64 is energized so as to close circuit-controller 67. This energizes the circuit of the home-signal magnet 38, as heretofore traced, magnet 38 thereupon closing circuit-controller 41 and completing the circuit of the motor heretofore traced through circuit-controller 41 and circuit-breaker 48, this latter circuit-breaker having been previously closed when the home-signal went to "danger." 85

The motor thereupon operates to move the signal to "safety" and to lock it there, as 95 heretofore described. When the home signal reaches safety position, circuit-breakers 46 and 47 are restored to their normally closed positions and circuit-breaker 48 is opened, thereby stopping the motor. When the train 100 enters block 63, it shunts track-magnet 65, which opens circuit-controller 77 and puts the signals for block 63 to "danger" in the same way as described with reference to signals 14 and 15. Circuit-controller 77 is in the circuit 105 of distant-signal magnet 54, and this circuit is again opened at circuit-breaker 79 as soon as home signal 84 for block 63 goes to "danger." When the train passes out of block 63, circuit-controller 77 closes and home signal 84 110 is put to "safety" in the same way as has been described with reference to home signal 14, thereby closing circuit-breaker 79. This completes the circuit of distant-signal magnet 54, which then closes circuit-controller 61 and 115 completes the circuit through the motor for the distant signal. This circuit, as already traced, extends through circuit-controllers 41 and 61, circuit-breaker 60, which was closed when distant signal went to "danger," and 120 through motor 6 to battery. Thereupon the motor operates to put distant signal 15 to "safety" and to lock it there, as heretofore described. When the distant signal reaches safety position, the motor-circuit is broken 125 at circuit-breaker 60 and the motor stops.

While this apparatus is herein shown and described in what is believed to be its best form, it will be understood that the details of the mechanism may be variously modified 130

without departing from the scope of the invention. It will be further understood that the apparatus may be successfully operated in conjunction with various arrangements of circuits, although the circuits as shown in Fig. 9 are preferred for ordinary installations.

What I claim, and desire to secure by Letters Patent, is—

1. The combination of a thrust-rod; a cam-piece adapted to engage with the thrust-rod; and a cam arranged to engage the cam-piece to move the thrust-rod, the thrust-rod having a return movement independent of the cam-piece.
2. The combination of a thrust-rod; a cam-piece adapted to engage with the thrust-rod; and a cam arranged to engage the cam-piece to move the thrust-rod, the thrust-rod having a return movement independent of the cam-piece; and means to control the engagement of the cam-piece and thrust-rod.
3. The combination of a thrust-rod; a cam-piece adapted to engage with the thrust-rod; and a cam arranged to engage the cam-piece to move the thrust-rod, the thrust-rod having a return movement independent of the cam-piece; and train-operated electric means to control the engagement of the cam-piece and thrust-rod.
4. The combination of a thrust-rod; a cam-piece adapted to engage with the thrust-rod; and a cam arranged to engage the cam-piece to move the thrust-rod, the thrust-rod having a return movement independent of the cam-piece; and locking means to hold the thrust-rod in the position to which it has been moved.
5. The combination of a thrust-rod; a cam-piece adapted to engage with the thrust-rod; and a cam arranged to engage the cam-piece to move the thrust-rod, the thrust-rod having a return movement independent of the cam-piece; means to control the engagement of the cam-piece and thrust-rod; and locking means to hold the thrust-rod in the position to which it has been moved.
6. The combination of a thrust-rod; a cam-piece adapted to engage with the thrust-rod; and a cam arranged to engage the cam-piece to move the thrust-rod, the thrust-rod having a return movement independent of the cam-piece; train-operated electric means to control the engagement of the cam-piece and thrust-rod; and locking means to hold the thrust-rod in the position to which it has been moved.
7. The combination of a thrust-rod; a cam-piece adapted to engage with the thrust-rod; and a cam arranged to engage the cam-piece to move the thrust-rod, the thrust-rod having a return movement independent of the cam-piece; and a stationary magnet to control the engagement of the cam-piece and thrust-rod.
8. The combination of a thrust-rod; a cam-piece adapted to engage with the thrust-rod; and a cam arranged to engage the cam-piece to move the thrust-rod, the thrust-rod having

a return movement independent of the cam-piece; and a stationary magnet to control said locking means and the engagement of the cam-piece and thrust-rod.

9. The combination of a thrust-rod; a cam-piece adapted to engage with the thrust-rod; and a cam arranged to engage the cam-piece to move the thrust-rod, the thrust-rod having a return movement independent of the cam-piece; and a magnet to control said locking means and the engagement of the cam-piece and thrust-rod.

10. The combination of a thrust-rod; a cam-piece adapted to engage with the thrust-rod; and a gear-wheel having thereon a cam arranged to engage the cam-piece to move the thrust-rod, the thrust-rod having a return movement independent of the cam-piece.

11. The combination of a thrust-rod; a reciprocating piece; means for engaging together said reciprocating piece and thrust-rod; a stationary magnet controlling said means; and a motor for moving said reciprocating piece and thrust-rod.

12. The combination of a thrust-rod; a reciprocating piece; means for engaging together said reciprocating piece and thrust-rod; a stationary magnet controlling said means; a motor for moving said reciprocating piece and thrust-rod; and means for holding the thrust-rod in the position to which it has been moved.

13. The combination of a thrust-rod; a reciprocating piece; means for engaging together said reciprocating piece and thrust-rod; a stationary magnet controlling said means; a motor for moving said reciprocating piece and thrust-rod; and means for holding the thrust-rod in the position to which it has been moved controlled by said magnet.

14. The combination of a thrust-rod; a reciprocating piece; means for engaging together said reciprocating piece and thrust-rod; a stationary magnet controlling said means; a motor for moving said reciprocating piece and thrust-rod; and a locking device for holding the thrust-rod in the position to which it has been moved.

15. The combination of a thrust-rod; a reciprocating piece; means for engaging together said reciprocating piece and thrust-rod; a stationary magnet controlling said means; a motor for moving said reciprocating piece and thrust-rod; and a locking device for holding said thrust-rod in the position to which it has been moved, said locking device having an operating-lever controlled by said magnet.

16. The combination of a thrust-rod; a reciprocating piece; means for engaging together said reciprocating piece and thrust-rod, said means including a moving latch and a stationary lever to hold the latch in engaging position during the movement of the thrust-rod; a stationary magnet controlling

gether said reciprocating piece and thrust-rod, said means including a moving latch and a stationary lever to hold the latch in engaging position during the movement of the thrust-rod; a magnet controlling said means; a cam for moving said reciprocating piece and thrust-rod; and a locking device operated by said lever for holding the thrust-rod in the position to which it has been moved, the lever being controlled by said magnet.

31. In a signal apparatus, the combination of a plurality of signals; a thrust-rod for each signal; a reciprocating piece for each thrust-rod adapted to engage with and move the same, each thrust-rod having a return movement independent of its reciprocating piece; and a single motor adapted to move each reciprocating piece and thrust-rod independently.

32. In a signal apparatus, the combination of a plurality of signals; a thrust-rod for each signal; a reciprocating piece for each thrust-rod adapted to engage with and move the same, each thrust-rod having a return movement independent of its reciprocating piece; a single motor adapted to move each reciprocating piece and thrust-rod independently; and a stationary magnet for each signal to control the engagement of its reciprocating piece and thrust-rod.

33. In a signal apparatus the combination of a plurality of signals; a thrust-rod for each signal; a cam-piece for each thrust-rod adapted to engage with and move the same, each thrust-rod having a return movement independent of its cam-piece; a cam for each cam-piece; and a single motor for driving said cams.

34. In a signal apparatus the combination of a plurality of signals; a thrust-rod for each signal; a cam-piece for each thrust-rod adapted to engage with and move the same, each thrust-rod having a return movement independent of its cam-piece; and a wheel having cams on opposite sides for moving said cam-piece and thrust-rod.

35. In a signal apparatus the combination of a plurality of signals; a thrust-rod for each signal; a cam-piece for each thrust-rod adapted

to engage with and move the same, each thrust-rod having a return movement independent of its cam-piece; and a gear-wheel having cams on opposite sides for moving said cam-piece and thrust-rod.

36. In a signal apparatus the combination of a plurality of signals; a thrust-rod for each signal; a reciprocating piece for each thrust-rod adapted to engage with and move the same, each thrust-rod having a return movement, independent of its reciprocating piece; a single motor adapted to move each reciprocating piece and thrust-rod independently; a locking device to hold each signal in the position to which it has been moved; and a stationary magnet controlling each locking device and also the engagement of the associated reciprocating piece with its thrust-rod.

37. In a signal apparatus the combination of a plurality of signals; a thrust-rod for each signal; a cam-piece for each thrust-rod adapted to engage with and move the same, each thrust-rod having a return movement independent of its cam-piece; a cam for each cam-piece; a single motor for driving said cams; a locking device to hold each signal in the position to which it has been moved; and a stationary magnet controlling each locking device and also the engagement of the associated cam-piece with its thrust-rod.

38. In a signal apparatus the combination of a plurality of signals; a thrust-rod for each signal; a cam-piece for each thrust-rod adapted to engage with and move the same, each thrust-rod having a return movement independent of its cam-piece; a wheel having cams on opposite sides for moving said cam-piece and thrust-rod; a locking device to hold each signal in the position to which it has been moved; and a stationary magnet controlling each locking device and also the engagement of the associated cam-piece with its thrust-rod.

In testimony whereof I have signed my name to this specification in the presence of two subscribing witnesses.

CLARENCE W. COLEMAN.
